US00D828483S

(12) **United States Design Patent** (10) **Patent No.:** **US D828,483 S**
Burrow (45) **Date of Patent:** **** Sep. 11, 2018**

(54) **CARTRIDGE BASE INSERT**

(71) Applicant: **True Velocity, Inc.**, Dallas, TX (US)

(72) Inventor: **Lonnie Burrow**, Carrollton, TX (US)

(73) Assignee: **True Velocity IP Holdings, LLC**,
Dallas, TX (US)

(**) Term: **15 Years**

(21) Appl. No.: **29/591,015**

(22) Filed: **Jan. 16, 2017**

Related U.S. Application Data

(60) Continuation of application No. 14/748,508, filed on Jun. 24, 2015, which is a continuation of application No. 14/320,961, filed on Jul. 1, 2014, which is a continuation of application No. 14/011,202, filed on Aug. 27, 2013, now Pat. No. 9,546,849, which is a division of application No. 13/292,843, filed on Nov. 9, 2011, now Pat. No. 8,561,543.

(57) **CLAIM**

The ornamental design for a cartridge base insert, as shown and described.

DESCRIPTION

FIG. 1 is an isometric view of a cartridge base insert showing my new design.

FIG. 2 is a side view of a cartridge base insert showing my new design.

FIG. 3 is a side view of a cartridge base insert showing my new design.

FIG. 4 is a top view of a cartridge base insert showing my new design.

FIG. 5 is a bottom view of a cartridge base insert showing my new design.

FIG. 6 is a cross sectional view of a cartridge base insert showing my new design; and,

FIG. 7 is an isometric cross sectional view showing the cartridge base insert molded into a cartridge casing.

The broken line showing of a cartridge casing shown in FIG. 7 is included for the purpose of illustrating environment and forms no part of the claimed design.

1 Claim, 5 Drawing Sheets
